(57) **CLAIM**

The ornamental design for a bottle opener, as shown and described.

DESCRIPTION

FIG. 1 is a perspective view of a bottle opener showing my new design;

FIG. 2 is a front view thereof;

FIG. 3 is a back view thereof;

FIG. 4 is a side view thereof;

FIG. 5 is another side view thereof;

FIG. 6 is a bottom view thereof; and,

FIG. 7 is a top view thereof.

The broken lines depict portions of the bottle opener and form no part of the claimed design.
